Primary Examiner — Vy N Koenig*(74) Attorney, Agent, or Firm* — Charmasson, Buchaca & Leach, LLP(57) **CLAIM**

The ornamental design for a patient lift, as shown and described.

DESCRIPTION

FIG. 1 is a top, front, left perspective view of a patient lift according to my new design.

FIG. 2 is a bottom back right perspective view thereof.

FIG. 3 is a front elevation view thereof.

FIG. 4 is a back elevation view thereof.

FIG. 5 is a top plan view thereof.

FIG. 6 is a bottom plan view thereof; and,

FIG. 7 is a right side elevation view thereof, the left side elevation view being a mirror image thereof.

Shading lines are used to show solid material and are not intended to indicate surface decoration.
